CLAIM

The ornamental design for a holster for a handgun, as shown and described.

DESCRIPTION

FIG. 1 is a front perspective view of a holster for a handgun showing my new design;

FIG. 2 is a front view thereof;

FIG. 3 is a right side view thereof;

FIG. 4 is a left side view thereof;

FIG. 5 is a top view thereof; and

FIG. 6 is a bottom view; and,

FIG. 7 is a front view of the holster with the environmental structure removed.

The back is plain and unadorned.

The objects shown in dotted lines are for ornamental purposes only and form no part of the claimed design.
